CASING PULLER AND CABLE GUIDE

Harold T. Provost, Sloansville, N. Y.

Application August 30, 1939, Serial No. 292,709

4 Claims. (Cl. 255—72)

The present invention relates to new and useful improvements in casing pullers and cable guides for well drilling machines and has for one of its important objects to provide, in a manner as hereinafter set forth, a device of this character comprising a novel construction and arrangement whereby a casing or drive pipe may be expeditiously pulled without the necessity of removing the drilling tool from the cable.

Another very important object of the invention is to provide a casing puller and cable guide of the aforementioned character embodying a unique construction whereby the device may be conveniently mounted on the cable and connected to the casing.

Still another important object of the invention is to provide a puller and guide of the character described which is adapted for connection to different sizes of casings or drive pipes.

A still further important object of the invention is to provide a device of the aforementioned character which, when used as a guide, will prevent the cable from "whipping."

Other objects of the invention are to provide a casing puller and cable guide of the character set forth which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is an elevational view of a casing puller and cable guide constructed in accordance with the present invention, showing the device installed and ready for use.

Figure 2 is a top plan view of the device.

Figure 3 is a view in vertical section through the device.

Referring now to the drawing in detail, it will be seen that the embodiment of the invention which has been illustrated comprises what may be referred to as a plug of any suitable metal which is designated generally by the reference numeral 1. The plug 1 includes a smooth, cylindrical upper end portion 2 beneath which are formed successively reduced, threaded portions 3 and 4. Further, the plug 1 terminates in a reduced, smooth lower end portion 5.

The reference numeral 6 designates a section

of casing on the upper end portion of which is a coupling 7. Extending downwardly into the casing 6 is a cable 8 having mounted on its lower end portion a drilling tool 9. The portion 3 of the plug 1 is adapted to screw into the coupling 7 thereby firmly connecting said plug to the casing 6. It may be well to here state that the portion 4 of the plug 1 is adapted to screw into casings of smaller diameter than that which has been illustrated. The lower end portion 5 of the plug 1 is adapted to fit into the smaller size casings.

Formed vertically in the plug 1 and extending from end to end thereof is a groove or channel 10. In depth, the groove 10 extends from the periphery of the plug 1 to the central portion thereof. The groove 10 slidably receives the cable 8.

Threadedly mounted in the upper portion 2 of the plug 1 is a removable bolt 11 which traverses the groove 10. A threaded bore 12 in the plug 1 accommodates the bolt 11. A recess 13 in the upper portion of the plug 1 accommodates the head 14 of the bolt 11. The bolt 11 constitutes a pin on which a peripherally grooved 25 guide roller 15 is journaled in the upper portion of the groove 10.

Extending into the upper portion 2 of the lug 1 is a socket 16 for the reception of a lever or handle to facilitate screwing said plug into or out of the coupling. Mounted on the upper end of the plug 1 is an eye bolt 17 to which a sand line may be conveniently connected to facilitate hoisting the device and screwing it into the casing.

It is thought that the manner in which the device functions will be readily apparent from a consideration of the foregoing. Briefly, the bolt 11 and the roller 15 are removed to permit the plug 1 to be slipped on the cable 8 and screwed into the coupling 7. The cable 8 and the tool 9 are then utilized to pull the casing, said tool striking the lower end 18 of the plug 1. As hereinbefore mentioned, when the device is being used as a cable guide the roller 15 prevents "whipping" of the cable.

It is believed that the many advantages of a casing puller and cable guide constructed in accordance with the present invention will be readily understood and although a preferred embodiment of the device is as illustrated and described, it is to be understood that changes in the details of construction and in the combination and arrangement of parts, may be re-

sorted to which will fall within the scope of the invention as claimed.

What is claimed is:

- 5 1. A casing puller and cable guide comprising a plug including means for connection with a casing, said plug having a vertical groove therein for the reception of a cable.
- 10 2. A casing puller and cable guide comprising a plug for connection with a casing, said plug having a vertical groove therein for the reception of a cable, and a retaining roller for the cable journaled in the groove.
- 15 3. A casing puller and cable guide comprising a plug including a threaded portion for connection with a casing, said plug having a vertical

groove therein for the reception of a cable, a removable pin mounted in the plug and traversing the groove, and a retaining roller for the cable journaled on said pin in the groove.

- 5 4. A casing puller and cable guide comprising a plug including a reduced, threaded intermediate portion adapted to be screwed into a casing, said plug terminating in a further reduced lower end portion adapted for insertion in the casing, said plug having a groove extending vertically therethrough for the reception of a cable, and a removable retaining roller for the cable journaled in the groove.
